UNITED STATES PATENT OFFICE.

HANS SIMENSEN, OF SUTTON, NORTH DAKOTA.

BOTTLE HOLDER AND CARRIER.

1,414,219.

Specification of Letters Patent. Patented Apr. 25, 1922.

Application filed January 24, 1921. Serial No. 439,623.

To all whom it may concern:

Be it known that I, HANS SIMENSEN, a citizen of the United States, residing at Sutton, in the county of Griggs and State of North Dakota, have invented certain new and useful Improvements in Bottle Holders and Carriers; and I do declare the following to be a full, clear, and exact description of the invention, such as will enable others skilled in the art to which it appertains to make and use the same.

This invention relates to an improved bottle holder and carrier, which is especially, although not necessarily, designed for use in connection with thermos bottles.

The principal object of the invention is to generally improve upon devices of this class by the provision of one of extreme simplicity and durability, the same embodying telescopically connected closed sections and a hand strap associated with the lower section, together with guide means between the upper section and strap to permit said section to be moved upwardly and disconnected from the lower section, after which, it may be swung to one side to clear the upper edge of said last section to permit easy insertion and removal of the bottle without disconnecting any of the parts of the device.

Other objects and advantages of the invention will be apparent during the course of the following description.

In the accompanying drawings forming a part of this specification and in which like numerals are employed to designate like parts throughout the same:

Figure 1 is an elevational view looking at one side of the combined holder and carrier, one of the telescopic sections having been moved up as shown in dotted lines, to permit it to be swung to one side for easy insertion and removal of the bottle.

Figure 2 is a view similar to Fig. 1 looking at a different side of the device.

Figure 3 is a horizontal section taken on the plane of the line 3—3 of Fig. 2, looking in the direction of the arrows.

In carrying out the invention, I make use of a vertically elongated substantially cylindrical receptacle 1, which is, as shown, composed of a pair of telescopically connected sections 2 and 3 respectively, said sections being closed at their outer ends. At this point, I wish to state that the receptacle will be of any desired length and will vary

in size and shape according to the type of bottle which is placed therein. The lower section 2 is provided intermediate its ends at diametrically opposite points with looped straps 4 which carry rings or similar elements 5 with which a hand strap 6 has detachable connection. It has been before intimated that with my construction, it is possible to separate the two sections, 2 and 3 and move the last named section to one side to permit easy insertion and removal of the bottle without removing the section 3 from the hand strap 6. To this end, I equip the section 3 intermediate its ends and at diametrically opposite points with substantially flat guide eyes 7 through which the opposite ends of the strap 6 extend, thus slidably connecting this section with the strap. At this point, I wish to direct attention to the fact that the strap 6 may, if desired, be made adjustable in order to permit various lengths of bottles to be accommodated or fitted into the receptacle 1. In accomplishing this end, any kind of a buckle either of the type shown or of any other type, may be employed. Furthermore, I wish it to be understood that all parts of the device are preferably constructed of leather, but any other kind of material could well be employed.

In use, it is understood that the hand strap 6 is practically permanently connected with the lower section 2 of the receptacle and when it is desired to place a bottle in the latter or remove one from it, it is only necessary to slide the upper section 3 upward on the other section as shown in dotted lines in Fig. 1. When in this position, the lower end of the section 3 and adjacent upper end of the other section will be in a position to clear each other, and the upper section can then be swung to either one side or the other to uncover the open end of the lower section and permit insertion or removal of the bottle as the case may be.

From the foregoing description, it will be seen that I have provided an extremely simple and effective holder for thermos bottles and the like which will permit the same to be conveniently carried from place to place and will serve as an effective protector for the bottle. As before stated, the size and shape of the receptacle will vary according to the type of bottle to be placed therein. It is also to be noted that, as already apparent, it is unnecessary to disconnect the upper section of the receptacle from the hand strap.

Thus, it will be seen that this section will always be in a convenient position to be swung over the upper end of the bottle and lower section and slid down onto the latter 5 to effectively retain the bottle in position in the receptacle and prevent undue loose movement of the bottle in said receptacle. These and other features and advantages of the invention have, no doubt, become apparent 10 from the foregoing description and drawing.

A careful consideration of the foregoing description taken in connection with the drawing is thought to be sufficient to enable persons skilled in the art to which the invention relates to obtain a clear understanding 15 of the same. Therefore, a more lengthy description is deemed unnecessary.

Since probably the best results may be obtained with the construction and arrangement 20 herein shown and described, this construction and arrangement is taken as the preferred embodiment of the invention. However, I wish it to be understood that various minor changes in the shape, size, and 25 arrangement of parts may be resorted to without departing from the spirit of the invention or the scope of the subjoined claim.

I claim:

A bottle holder and carrier comprising a vertically elongated container composed of 30 a lower cylindrical section and an upper cylindrical cover section fitted over the upper open end of the lower section, loops secured to said lower section at approximately diametrically opposite points adjacent the upper open end of the latter guide eyes secured at approximately diametrical opposite points on said cover section, being disposed in vertical alignment with said loops, and a flexible hand strap detachably and adjustably connected at its lower ends with said loops, passing through said guide eyes, whereby the cover section can be slid upwardly on the hand strap so that it will 35 clear the upper edge of the lower section of the container, and the hand strap flexed to one side to uncover the open end of the lower section without detaching the hand strap or without removing the cover section from the latter. 40

In testimony whereof I have hereunto set my hand.

HANS SIMENSEN.
